(57) CLAIM

I claim the ornamental design for a bag, as shown and described.

DESCRIPTION

FIG. 1 is a front view of a bag according to the first embodiment of the invention; and,

FIG. 2 is a perspective view of the bag thereof.

The broken lines in the drawings of the bag are for showing portions of the article and form no part of the claimed design.

1 Claim, 2 Drawing Sheets
